Emerson Kijima

UNITED STATES PATENT OFFICE.

KENJI KIJIMA, OF LOS ANGELES, CALIFORNIA.

ELECTRIC SWIVEL SOCKET.

Application filed January 31, 1921, Serial No. 441,361. Renewed January 24, 1924.

To all whom it may concern:

Be it known that I, KENJI KIJIMA, a subject of the Emperor of Japan, residing in the city and county of Los Angeles and State 5 of California, have invented a new and useful Electric Swivel Socket, of which the following is a specification.

The present invention relates to electrical appliances and more particularly to provide 10 a swivel joint for electrical conductors, which will permit the same to be twisted, turned, and handled without becoming tangled, without breaking, and without interruption of the circuit, the device being especially adapted for use with portable electric apparatus, such as lamps, telephones, 15 motor fans and the like.

To these and other ends, the invention resides in certain improvements and combination 20 of parts all as will be more fully and hereinafter described and pointed out in the appended claims.

In the drawings, Figure 1 is a side view of my improved electric swivel socket. 25 Fig. 2 is a side view of the same, with parts of the casing withdrawn partly from the assembled position. Fig. 3 is a plan view of the ring which retains the casing in assembled form. Fig. 4 is a side or edge view of 30 the retaining ring. Fig. 5 is a perspective view of an inner insulating member. Fig. 6 is a bottom plan view of the contact elements forming the inner telescoping part of the device. Fig. 7 is a top plan view of 35 the contact elements forming the outer telescoping part of the device. Fig. 8 is a perspective and detail view of the inner contact member. Fig. 9 is a perspective and detail view of the contact member which co-acts 40 with the inner contact member. Fig. 10 is a transverse and sectional view of the inner telescoping member with the metallic casing removed. Fig. 11 is a perspective view of a connecting element. Fig. 12 is a 45 sectional detail view of a telescoping member. Fig. 13 is a perspective view of an insulating block.

Referring more particularly to the drawing, a metallic outer casing member 21, is 50 swivelly connected to a corresponding casing member 22, which terminates in a flange 23 to form the annular groove 24 between the flange 23 and the knurled portion 25. A ring 26, fixed to casing member 21, by screws 55 27, is mounted in groove 24. The upper insulating member 28, preferably of porcelain,

is mounted within casing member 22, being retained by screws 29 which pass through an insulating member 30, preferably constructed of paper. Member 28, has mounted thereon a contact member 31, to which is attached the connecting element 32, separated from the paper member 30, by a wax insulating element 33. The inner and central contact element 40 is fixed to the connector element 34, and binding screws 35 are provided for connecting electrical conductors thereto. An insulating member 36, preferably of paper, is provided.

The outer casing member 21 has mounted therein the insulating block 37, on which are mounted the contact member 38, adapted to cooperate with contact member 31, and contact member 39, adapted to cooperate with contact member 40, both contact members 38 and 39 consisting of fingers designed to grasp the corresponding contact member, and having connectors 32 and 34, respectively.

It will be seen that this invention provides a swivel joint for electric conductors, and that a constant contact may be retained and all twisting strains on the conductors avoided, and when assembled, the parts cannot be separated.

What is claimed is:

1. In an electric swivel socket, the combination with an outer telescoping casing, a lining therefor of insulating material, an inner insulating member relatively fixed to 90 the casing, and two contact members, constituting, respectively outer and inner concentric and flexible shells completely enclosed within the casing and its lining of insulating material, comprising a plurality 95 of outwardly yielding spring fingers formed with inwardly projecting extremities, of an inner telescoping casing and lining therefor of insulating material, a second inner insulating member relatively fixed to the inner 100 casing, two contact members carried by the inner insulating member engaging with the yielding fingers of the outer contact members, an annular flange on the inner casing and disposed within the outer casing, a 105 knurled flange on the inner casing and disposed without the outer casing, a detachable ring on the outer casing and disposed between the flanges on the inner casing, and screws securing the detachable ring to the 110 outer casing.

2. In an electric swivel socket, the combi-

nation with an outer telescoping casing, a lining therefor of insulating material, an inner insulating member relatively fixed to the casing, and two contact members consisting of concentric and yieldable fingers, mounted on the insulating member, of an inner telescoping casing, insulating lining therein, an insulating member therein, contact members mounted therein and cooperating with the yieldable fingers, means for connecting electric terminals to the contact members, and means for maintaining the telescoping casings in rotatable connection with one another.

5 10 15 3. Telescoping casings axially rotative

relative to one another, annular flanges on the inner casing, a ring disposed between the annular flanges, screws securing the ring to the outer casing, contact members insulated from one another and insulated from the inner casing and rotatable with said inner casing, cooperative contact members insulated from one another and insulated from the outer casing and rotatable with said outer casing, and means for connecting electric terminals with said contact members.

In testimony whereof I affix my signature this 31st day of December, 1920.

KENJI KIJIMA.
